WILLIAM J. KELLY, OF BROOKLYN, NEW YORK, ASSIGNOR OF ONE-HALF TO ARTHUR C. BASCH, OF BROOKLYN, NEW YORK

METHOD OF MAKING SHOES

Application filed January 30, 1930. Serial No. 424,490.

This invention relates to improvements in the method or art of making shoes and the principal object is the new and improved method whereby shoes may be made with a minimum amount of material, a minimum wastage and may be completely and uniformly lasted, well fitting, finished in appearance and have various other numerous advantages hereinafter set forth.

10 To the accomplishment of the foregoing and such other objects as may hereinafter appear, this invention consists in the art or method of making shoes disclosed in the drawings and described in the specification 15 and sought to be defined in the appended claims, it being expressly understood that changes may be made in practice within the scope of the claims without digressing from my inventive idea.

20 In the drawings—

Figure 1 represents a side elevation of a shoe in the process of manufacture with the upper assembled on the last.

25 Figure 2 is a vertical transverse cross section taken through the front portion of the assembly shown in Figure 1 showing the manner in which the upper is pulled over the last.

30 Figure 3 is a similar view showing the manner in which the lower part of the upper is wiped or forced in against the lower side edge portions of the last.

35 Figure 4 is a similar view showing the tacks driven into the sides of the last adjacent the bottom and near the edges of the same, this operation taking place at the same time that the wiping operation takes place.

40 Figure 5 is a similar view showing the first sole applied to the last and then the upper pulled over.

Figure 6 is a cross sectional view showing the step of sewing the upper to the first sole.

45 Figure 7 is a perspective view showing a portion of the upper and sole after the sewing operation is complete and showing how the stitch goes over the tack to hide the hole made by the tack.

50 This application is a continuation in part of my prior copending applications Serial

No. 95,853 filed March 19, 1926, and Serial No. 385,390 filed August 12, 1929.

In the drawings the numeral 1 designates the last and 2 the upper. The first sole is designated by the reference character 3, the 55 side tacks by 4 and the stitching by 5.

The first step involves the assembling of the upper on the last and the pulling of the upper over the last, as indicated in Figure 2. This is accomplished by the pull-over mechanism designated generally by the reference character 6, whereby the upper is pulled simultaneously downwardly and outwardly on opposite sides of the last, as clearly shown in Figure 2, so that the bottom edges of the upper extend outwardly at a decided angle 60 away from the lower side portions of the last.

The next step involves the pushing or wiping in of the upper against the lower side 70 portions of the last. This is accomplished by the wiping mechanism shown generally in Figure 3 and designated by the reference character 7. This forces a part of the upper tightly against the sides of the last and forms 75 the angle indicated by the reference character 8.

At or about this time the side tacks 4 are driven through the upper into the lower side 80 portions of the last at an angle so that the head portions of the tacks extend downwardly. These tacks are driven into the sides of the last at or near the angle or bottom edge 85 of the same, as clearly shown in Figure 4. When this operation is complete, the lower edges of the upper are in the position clearly shown in Figure 4.

The next step is the placing of the first sole 3 on the wholly or partially lasted upper, 90 this sole in one form being of the same width as the last plus the sides of the upper. It may be secured to the last by tacks 9 (see Figure 6). When this sole is placed in position, the side edges of the upper which were bent to extend substantially at right angles 95 to the lower side edges of the last, rest flatly upon the sides of the sole itself, as clearly shown in Figure 6.

This assembly is next placed upon the tilting table construction 10 disclosed in my prior 100

application Serial No. 95,853 and stitched by the stitching mechanism designated generally by the reference character 11. The stitches 5 are formed through the sharp angle 8 above referred to and when the lasted upper is being sewed, it is so handled on the tilting table that the stitching is very tight and close to the edges of the last and also goes over the side tacks 4, as indicated in Figure 6 and clearly shown in Figure 7.

10 This results in a completely and accurately lasted shoe and the hiding of any holes which may be left by the tacks 4 when withdrawn.

15 In the modification of the process shown in Figure 5, I first tack a sole 3 on the last 1. This sole is wider than the bottom of the last, leaving the marginal edge. The upper 2 is then placed on the last and the edges thereof are drawn down and outwardly from 20 the edge of the bottom of the last to the outer edge of the insole or beyond the same. The upper is then forced inwardly into the angle between the bottom of the last and the sole, allowing the out-turned edge of the upper 25 to rest on the marginal edges of the sole. Tacks are driven into the side of the last as near the bottom thereof as possible, and the rest of the operation is the same.

What I claim is:—

30 1. In the art of making shoes, the process which consists in pulling an upper downwardly and outwardly simultaneously from the bottom edge of the last at opposite sides thereof, then forcing the upper inwardly against the lower portion of the last and driving tacks through the upper into the sides of the last at or near the bottom edge of the same, placing a sole against the last with its edge supporting the free out-turned edge 35 of the upper at a substantially right angle to the last and upper, and then stitching this assembly through the angle of the upper.

2. In the art of making shoes, the process which consists in pulling an upper downwardly and outwardly from the bottom edge of the last, then forcing the upper inwardly against the lower portion of the last and driving tacks through the upper into the sides of the last at or near the bottom edge 50 of the same, placing a sole against the last with its edge supporting the free out-turned edge of the upper at a substantially right angle to the last and upper, and then stitching this assembly through the angle of the upper and at an angle to the sole, and over the tacks so as to pull the tacks down upon the sole and to hide the holes left by the tacks 55 when they are afterwards withdrawn.

3. In the art of making shoes, the process 60 which consists in pulling an upper downwardly and outwardly from the bottom edge of the last, then forcing the upper inwardly against the lower portion of the last and driving tacks through the upper into the sides 65 of the last at or near the bottom edge of the

same at an angle to the bottom of the last, placing a sole against the last with its edge supporting the free out-turned edge of the upper at a substantially right angle to the last and upper, and then stitching this assembly through the angle of the upper, the securing of the same resulting in bending the tacks slightly upward.

4. In the art of making shoes, the process which consists in pulling an upper downwardly and outwardly from the bottom edge of the last, then forcing the upper inwardly against the lower portion of the last and driving tacks through the upper into the sides of the last at or near the bottom edge 75 of the same at an angle to the bottom of the last, placing a sole against the last with its edge supporting the free out-turned edge of the upper at a substantially right angle to the last and upper, and stitching this assembly through the angle of the upper in line with the tacks, whereby the securing of the same results in bending the tacks slightly upward, and the stitching hides the holes left by the withdrawal of the tacks.

5. In the art of making shoes, the process which consists in assembling a sole upon a last which is wider than the bottom of the last, placing an upper on the last and pulling the edge of the upper down to or over the edge of the sole so that the upper extends at an angle to the lower portion of the last, forcing the lower portion of the upper inwardly toward the last into the angle between the last and the upper surface of the sole, and tacking the upper to the last by tacks driven into the sides of the last as near to the bottom thereof as possible.

6. In the art of making shoes, the process which comprises pulling an upper downwardly and outwardly simultaneously from the edge of the last at opposite sides thereof, turning the free edge of the upper outwardly at a sharp angle to the upper, and driving tacks through the upper and into the side of the last near the bottom thereof.

7. In the art of making shoes, the process which consists in assembling an insole on a last with the edge of the insole projecting beyond the bottom edge of the last, pulling an upper downwardly and outwardly from the edge of the last to or over the edge of the insole, and driving tacks through the upper and into the side of the last near the bottom edge of the same so that the free edge of the upper abuts and rests upon the upper surface of the edge of the insole.

8. The method of making shoes which comprises pulling an upper downwardly and outwardly simultaneously from the bottom edge of the last on opposite sides thereof, forcing the upper inwardly against the lower portion of the last, and driving tacks through the upper into the sides of the last at or near the bottom edge of the same, placing a sole 125

against the last with its edge supporting the free out-turned edge of the upper at a substantially right angle to the last and upper, and stitching this assembly through the angle of the upper and over the tacks so as to pull the tacks down upon the sole and to hide the holes left by the tacks when they are afterwards withdrawn.

9. In the method of making shoes, the steps of pulling an upper downwardly and outwardly simultaneously from the bottom edge of the last at opposite sides thereof, and driving tacks through the upper and into the side of the last.

15 In testimony that I claim the foregoing, I have hereunto set my hand this 27th day of January, 1930.

WILLIAM J. KELLY.
